UNITED STATES PATENT OFFICE.

WILLIAM P. CHAMPNEY, OF CLEVELAND, OHIO.

FIFTH-WHEEL.

SPECIFICATION forming part of Letters Patent No. 544,155, dated August 6, 1895.

Application filed June 27, 1894. Serial No. 515,810. (No model.)

To all whom it may concern:

Be it known that I, WILLIAM P. CHAMPNEY, of Cleveland, in the county of Cuyahoga and State of Ohio, have invented a new and useful Improvement in Fifth-Wheels, of which the following is a full, clear, and exact description, reference being had to the accompanying drawings, forming part of this specification, in which—

10 Figure 1 is a top plan view of my improved fifth-wheel. Fig. 2 is a cross-section on the line II II of Fig. 1.

15 My invention relates to the McLaughlin type of fifth-wheels and is designed to strengthen and improve the construction of such wheels.

20 In the drawings, 2 is the axle, 3 the axle-bed, and 4 the top axle-plate, carrying at its outer ends the sections 5 of the lower circle-plate. This plate is provided with a central circular opening to receive a boss upon the tubular socket 6 of the upper perch-iron and is secured to the axle by front and rear flanges 7 and 8, which are bolted through the axle. The upper perch-iron is secured to the head-block 9 by bolts 10, passing through a flange 11, which is cast integral with the perch-iron, and secured to the head-block by clips 12 is

the head-plate 13, having a circular opening to receive an upwardly-projecting boss upon the tubular socket and carrying the segments 30 of the upper circle-plate 16. The king-bolt 14 passes through the head-block, tubular socket, and axle and is secured by end nuts, as shown, the lower nut holding the lower perch-iron 15 in place. 35

The advantages of my invention consist in the increased strength and durability of the wheel.

I claim—

25 A fifth-wheel, having a top axle-plate provided with a central aperture to receive a tubular socket upon the perch-iron, said plate having continuous depending front and rear flanges extending past the central aperture and arranged to strengthen the axle at the 40 point where it is weakened by the king-bolt hole, said flanges being connected by transverse bolts, substantially as described. 45

In testimony whereof I have hereunto set my hand.

WILLIAM P. CHAMPNEY.
